UNITED STATES PATENT OFFICE.

HARRY HUGH STEELE, OF PARIS, ILLINOIS.

ROOFING SLAB.

Application filed June 27, 1921. Serial No. 480,760.

To all whom it may concern:

Be it known that I, HARRY H. STEELE, a citizen of the United States, residing at Paris, in the county of Edgar and State of Illinois, have invented new and useful Improvements in Roofing Slabs, of which the following is a specification.

This invention relates to an improved roofing slab of the type which are made to represent shingles, the principal object of 10 the invention being to prevent the lower ends of the slabs from curling up under the action of the wind or sun.

Another object of the invention is to 15 cover the slots formed in the lower part of the slab which divide said slab into portions for representing a number of shingles.

These objects are secured by making the lower part of the slab of double thickness, 20 the under layer being of greater width than the length of the slots.

This invention also consists in certain other features of construction and in the combination and arrangement of the several parts, to be hereinafter fully described, 25 illustrated in the accompanying drawings and specifically pointed out in the appended claims.

In describing my invention in detail, reference will be had to the accompanying 30 drawings wherein like characters denote like or corresponding parts throughout the several views, and in which:—

Figure 1 is a face view of a slab constructed in accordance with my invention.

Figure 2 is a section on line 2—2 of Figure 1.

Figure 3 is a fragmentary plan view of a roof covered with my slabs.

As shown in these views the slab 1 has a strip 2 on its under face which extends 40 from the lower edge to a point above the inner ends of the slots 3. This strip may either be a separate strip placed on the slab or it may be a continuation of the slab turned over, as shown in the drawings. The ends of this strip are cut off on an incline, as shown at 4 and 4', one end of the strip being shorter than the slab to provide 45 a recess 5 and the other end projects beyond the end of the slab. This will permit the slabs to be readily positioned as the projecting end on one slab will engage the recess of the adjacent slab. Thus the slabs can be put on the roof very quickly 50

and easily and laying off of the roof is unnecessary.

The slab can be made of any suitable material though I prefer to make it of the usual flexible roofing material now on the market. 60

A slab constructed in accordance with my invention will have its ends or butts of twice the thickness of an ordinary slab so that the shadows produced will add to the ornamental effect of the roof. Also there is no danger of the parts of the slabs between the slots curling up due to the effect of the elements as is the case with slabs of a single thickness, as the slotted portions 70 are held against curling action by the strip 2 placed underneath them and this strip also sheds water passing through the slots 3. The double thickness of the lower part of the slab gives a massive ornamental 75 effect so that my improved shingle is more ornamental than a shingle of a single thickness, it eliminates curling of the ends of the slotted parts and its water shedding qualities are increased. 80

It is thought from the foregoing description that the advantages and novel features of my invention will be readily apparent.

I desire it to be understood that I may 85 make changes in the construction and in the combination and arrangement of the several parts, provided that such changes fall within the scope of the appended claims. 90

What I claim is:—

1. A new article of manufacture comprising a roofing slab having a reinforcing strip on its under side at its lower part, 95 said strip having laterally offset ends so as to provide a recess at one end of the slab and a corresponding projection at the other end thereof.

2. A new article of manufacture comprising a roofing slab having slots in its lower part and a reinforcing strip connected with the bottom face of the slab at the lower part thereof, said strip being of greater width than the length of the slots so as to entirely cover said slots. 100

3. A new article of manufacture comprising a roofing slab having its lower part folded over upon its bottom face to make the lower part of the slab of double thickness, the top thickness being slotted to 110

imitate shingles and said slots being covered by the folded part.

4. A new article of manufacture comprising a roofing slab having a reinforcing strip on its under side at its lower part, said strip having laterally offset ends so as to provide a recess at one end of the slab and a corresponding projection at the other end thereof, the ends of the strip being inclined and the lower part of the slab above the strip being slotted.

5. A roofing strip unit comprising a strip folded back on itself, the folded edge being exposed to the weather when the strip is laid, the upper layer being notched out to

form individual roofing unit simulating tabs, and the lower layer extending from said folded edge to the full extent of said notches.

6. A roofing strip unit comprising a strip 20 folded back on itself, the folded edge being exposed to the weather when the strip is laid, the upper layer being notched out to form individual roofing unit simulating 25 tabs, and the lower layer extending from said folded edge beyond the upper ends of said notches.

In testimony whereof I affix my signature.

HARRY HUGH STEELE.
